Patented Oct. 7, 1975

237,111

SEWING MACHINE BELT GUARD OR SIMILAR ARTICLE

George D. La Police, Somerville, N.J., assignor to The Singer Company, New York, N.Y.

Filed Feb. 21, 1974, Ser. No. 444,592

Term of patent 14 years

Int. Cl. D15—06

U.S. Cl. D70—2 A

Fig. 1

FIG. 1 is a front perspective view of the sewing machine and belt guard showing my new design; and

FIG. 2 is a rear perspective view thereof.

I claim:

The ornamental design for a sewing machine belt guard or similar article, substantially as shown.
